INVENTOR:
John F. Norton.

by his atty *Charles N. Gooding*

UNITED STATES PATENT OFFICE.

JOHN F. NORTON, OF BOSTON, MASSACHUSETTS.

PISTON.

Application filed March 29, 1923. Serial No. 628,459.

To all whom it may concern:

Be it known that I, JOHN F. NORTON, a citizen of the United States, residing at Boston, in the county of Suffolk and State 5 of Massachusetts, have invented new and useful Improvements in Pistons, of which the following is a specification.

This invention relates to an improved piston particularly adapted for use in the 10 cylinders of internal combustion engines.

The object of the invention is to provide a piston which will prevent carbonized matter formed within the combustion chamber of an engine from becoming permanently de- 15 posited upon the outer surface of the end wall of the piston.

This invention is an improvement as to 20 specific arrangements of depressions, the same being broadly claimed in an application for Letters Patent by me filed February 7, 1923, Serial No. 617,474. The specific arrangement of grooves or depressions in the end wall of the piston embody intersecting grooves which may be either straight or 25 curved.

The invention further embodies a piston having pyramidal projections on the outer end wall.

The invention further consists in a piston 30 with depressions in its outer end wall as set forth in the several claims hereunto appended.

Referring to the drawings:

Figure 1 is an end view of a piston embodying one form of my invention.

Fig. 2 is an end view embodying another form of my invention.

Fig. 3 is a transverse section taken on line 3—3, Figure 1.

Fig. 4 is a transverse section taken on line 4—4, Figure 1.

Fig. 5 is an end view of another embodiment of my invention.

Fig. 6 is an end view of still another embodiment of my invention.

Like numerals refer to like parts throughout the several views of the drawings.

In the drawings, referring to Figs. 1 and 3, 10 represents a piston of an internal combustion engine, said piston being of well-known construction, except as to the grooves in the outer end wall thereof and provided adjacent the upper closed end with a plurality of annular grooves 11 extending around

the periphery thereof, in each of which is 55 located a piston ring 12 of the usual well-known construction.

The closed outer end 13 of the piston is provided with a plurality of straight depressions or grooves 14 which extend entirely 60 across the outer end of the piston and are separated from each other by inverted V-shaped ridges 15. The grooves 14 and ridges 15 are provided for the purpose of eliminating the smooth surface heretofore always 65 found on the outer end of a piston and as the piston expands and contracts with the alternate heating and cooling which it undergoes, there is a tendency caused by the presence of the grooved outer end surface to 70 break up any incrustation of carbonized matter which may be formed thereon while the engine is running and thereby prevent said carbonized matter from collecting upon said outer surface and becoming permanently attached thereto. 75

In Figs. 2 and 4 the outer end surface of the piston 16 is provided with pyramidal projections 17 formed by a plurality of intersecting V-shaped grooves 18 and 19. 80

In Fig. 5 a plurality of concentric grooves 20 are provided in the outer end wall of a piston 21, which are separated from each other by inverted V-shaped curved ridges 22. The grooves and ridges are of the same 85 shape in cross section, as the grooves and ridges in Fig. 3.

In Fig. 6 a piston 23 is provided with a plurality of concentric grooves 24 which intersect a plurality of concentric grooves 25, 90 thus forming diamond-shaped pyramidal projections 26.

I claim:

1. A piston for high-speed internal combustion gasoline engines embodying therein 95 a closed end wall provided with intersecting grooves upon the outer end surface thereof.

2. A piston for high-speed internal combustion gasoline engines embodying therein 100 a closed end wall provided with intersecting depressions upon the outer end surface thereof.

3. A piston for high-speed internal combustion gasoline engines embodying therein 105 a closed end wall provided with intersecting straight grooves upon the outer end surface thereof.

4. A piston for high-speed internal combustion gasoline engines embodying therein a closed end wall provided with straight grooves upon the outer end surface thereof the width of said grooves being greater than their depth.
5. A piston for high-speed internal combustion gasoline engines embodying therein a closed end wall provided with pyramidal
- projections upon the outer end surface thereof.
- In testimony whereof I have hereunto set my hand in presence of two subscribing witnesses.

JOHN F. NORTON.

Witnesses:

CHARLES S. GOODING,
FRANKLIN E. LOW.
